UNITED STATES PATENT OFFICE.

GEORGE G. DARR AND PETER W. ESCHMAN, OF SHARPSBURG,
PENNSYLVANIA.

DESIGN FOR A BOTTLE.

SPECIFICATION forming part of Design No. 33,459, dated October 30, 1900.

Application filed September 4, 1900. Serial No. 29,008. Term of patent 14 years.

To all whom it may concern:

Be it known that we, GEORGE G. DARR and PETER W. ESCHMAN, citizens of the United States of America, residing at Sharpsburg, in the county of Allegheny and State of Pennsylvania, have invented and produced a certain new and original Design for Bottles, of which the following is a specification, reference being had therein to the accompanying drawing.

This invention relates to certain new and novel designs for bottles, of which the following is a specification, reference being had to the accompanying drawing, forming a part thereof.

The figure is a side elevation of a bottle showing our new design.

As shown in the drawing, the leading or material feature of our design consists of a bottle 1, having a terminal 2 gradually reducing in diameter to the top, the exterior surface of the bottle and terminal being smooth, with

the exception of a circular recess 4 in the bottle-body, the wall of this recess being at direct right angles to the length of the bottle. 3 denotes an interior annular groove in the inner wall of the terminal near its upper end, and 5 denotes an annular bead, which surrounds the bottle at its base. 25

It will be noted that the bottle presents a 30 symmetrical appearance to the eye and the outer contour-lines of the bottle forming distinctive features of originality in the design.

What we claim as new, and desire to secure by Letters Patent, is--

The design for a bottle, as herein shown and described.

In testimony whereof we affix our signatures in the presence of two witnesses.

GEORGE G. DARR.

PETER W. ESCHMAN.
